UNITED STATES PATENT OFFICE.

NOIBERTO GUY COPLEY, OF FOSTORIA, OHIO, ASSIGNOR TO THE "S. C." REGULATOR COMPANY, OF FOSTORIA, OHIO, A CORPORATION OF OHIO.

WATER-LEVEL REGULATOR.

970,421.

Specification of Letters Patent. Patented Sept. 13, 1910.

Application filed February 6, 1909. Serial No. 476,379.

To all whom it may concern:

Be it known that I, NOIBERTO GUY COPLEY, a citizen of the United States, residing at Fostoria, in the county of Seneca and State of Ohio, have invented a certain new and useful Improvement in Water-Level Regulators, of which the following is a full, clear, and exact description, reference being had to the accompanying drawings.

This invention relates to devices for maintaining the water in a boiler at the desired level, the same being an improvement upon the device shown in the patent to Robert L. Short, No. 743,108.

The invention consists generally of what I term a "generator," the same comprising a tube, the ends of which are respectively in communication with a boiler below and above the water line, said tube being bent into a U-shape and lying substantially in the same plane with the water level in the boiler, and a thin metallic casing surrounding the bent part of the tube, said casing being adapted to be partially filled with a medium that is capable of expanding when subjected to the heat in the tube whenever the water level falls below the plane of said tube so as to admit live steam thereto. The expanded medium acts upon a diaphragm controlling the water supply, the inflation of the diaphragm causing a balanced valve to be opened so as to supply additional water to the boiler. Whenever the water in the boiler rises to the desired level, said tube fills with water and the thin metallic shell cools, condensing the vapor generated while steam was in the tube, thus decreasing the pressure of the medium upon the said diaphragm, whereupon the valve is closed, thus decreasing the water supply to the boiler.

Referring to the drawings forming a part hereof, Figure 1 is a view, more or less diagrammatic, showing a portion of a boiler with my invention applied thereto; Fig. 2 is a perspective view showing a portion of the water column of the boiler with the generator attached thereto. Fig. 3 is a vertical section through the said generator, the bent tube thereof being shown in elevation; Fig. 4 is a transverse section through Fig. 3 on the line 4—4 thereof; and Fig. 5 is a longitudinal section through the valve and

the controlling mechanism connected therewith.

55

Taking up a more detailed description of the invention by the use of reference characters, 1 represents the boiler having a steam dome 2.

3 is the water column of the boiler, the same being provided with the ordinary glass gage 4. Connected to the lower end of the water column is a pipe 5 leading to the boiler below the water level, said level being indicated by the line A. Attached to the upper end of the water column is a pipe 6, which leads to the steam dome 2, or to some other point of the boiler above the water line. It is, of course, understood that the water in the column 3 will rise to 70 the same level as the water in the boiler.

Attached to the water column is a pipe-connection 7, to which is joined one end of a small pipe 8, said pipe being bent into a U-shape near its center,—the bent portion 75 of the pipe being completely surrounded by a closed metallic casing 9, said casing being preferably formed of thin copper. The lower end of the pipe 8 is connected with a pipe connection 10 which is joined to a pipe 11 that is in turn connected through a T 8^a with the water column 3 below the water level of the boiler. The bent portion of the pipe 8 lies just below the normal water level in the boiler, so that the bend in the pipe 8 85 is normally filled with water. The rear wall of the casing 9 is provided with an opening through which water or other medium may be introduced into the casing, after which the opening is adapted to be closed by a 90 plug 12 screwed therein. The water in the casing 9 normally stands just above the bend in the pipe 8 so that the said pipe is submerged in the water. Leading from the casing 9 near the lower end thereof is a pipe 95 13, said pipe extending to the upper part of a casing 14 containing a diaphragm 15. The diaphragm and casing are supported by means of a yoke 16 from a valve casing 17, which, as shown, is placed in a steam pipe 18 leading to a pump 19. This pump has a water cylinder 20 for pumping water to the boiler 1 through the pipe 21.

While it is convenient to attach the generator to the water column, as shown and described, this means of connection is by no 105

means necessary, as it may be connected to the boiler in any other suitable position.

A detail of the valve casing 17 is shown in Fig. 5, from which it will be seen that the casing has a pair of internal valve seats 22 and 23, with which coöperate valve-disks 24 and 25, said disks being normally held in contact with the said seats by a coiled spring 26 which surrounds the valve stem 27. A pair of valve-disks is thus used so as to secure a balanced effect, thus rendering the valve more sensitive to changes in pressure. The valve casing is closed on its lower side by a cage 28, which cage is provided in its lower end with a socket 29 for receiving the lower end of the stem 27, said cage also supporting the lower end of the spring 26. Above the disks 24 and 25 projects a stem 30, said stem having on its upper end a plate 31, which rests against the lower side of the diaphragm 15. With this construction, it will be understood that when the water in the boiler is at the desired level, as indicated by the line A, the bent portion of the pipe 8 within the casing 9 is filled with water, while the water in the said casing substantially covers the pipe. Under these circumstances, the pressure within the casing 9 and upon the diaphragm 15 will not be sufficient to materially depress the diaphragm, and the disks 24 and 25 are therefore maintained substantially in their closed positions. When, however, the level in the boiler falls below the bent portion of the pipe, the latter becomes filled with steam, which partially evaporates the water or other medium in the casing 9, thus creating a pressure therein, which, acting upon the upper side of the diaphragm, depresses the plate 31 and the disks 24 and 25 so as to open the valve. Additional steam is thus supplied to the pump 19, which supplies an additional quantity of water to the boiler, the pump being maintained in operation until the desired water level is again reached, when the bent portion of the pipe 8 again fills with water, cools, and condensation in the casing 9 removes the pressure therein, which results in the closure of the valve and the stoppage of the pump.

The above description applies when my invention is used for controlling the supply of steam to the pump. This is the manner in which I contemplate using the invention where a single boiler is to be controlled. Where a battery of boilers are to be controlled, I prefer to place controlling valve disks 24 and 25 in the water supply pipes 21, there being one of said sets of disks and 60 controlling devices for each of the boilers. When thus employed, the pump may continue to operate, but the amount of water supplied to any one boiler will be controlled by the valve in the water supply pipe for 65 that boiler.

In operation, water or some other suitable medium is introduced through the opening for the plug 12 in the casing 9 until the space above the diaphragm, the pipe 13 and the casing 9 up to said plug are filled. The bent part of the tube 8 lies in a plane that is slightly inclined from the horizontal so that the water will run out of the pipe from below and admit the steam from above whenever the water level falls. This same plane 75 may be substantially maintained although the casing 9 may be raised or lowered; for by turning the pipe connection 10 about an axis coincident with the pipe 11, the T 8^a and the corresponding side of the pipe 8 are 80 lifted. If the pipe connection 7 be, at the same time, turned a like amount the other side of the pipe 8 is also lifted and the former plane of the bent portion of the pipe is thus maintained. 85

In order to hold the valve open when no steam is in the boiler or when it is desired to pump water into the boiler above the normal water-line where the generator is located, or to throw the regulator out of 90 operation should occasion require, I provide screw threads upon the stem 30 at 32, upon which is a threaded hand wheel or nut 33, said wheel or nut being adapted to be screwed against a stationary brace 34 that extends 95 between the yoke bars 16. By screwing upon this wheel or nut, the valve disks are forced open and the plate 31 is separated from the diaphragm.

Various modifications in details of construction may be made without departing from the spirit of my invention, and I desire it to be understood that the following claims are not intended to be limited to such details any further than may be necessitated 105 by their specific terms and by the prior state of the art.

Having thus described my invention, what I claim is:

1. The combination, with a boiler and means for feeding water thereto, of mechanism for controlling said feeding means including a valve casing, a valve in said casing, means for normally holding said valve in its closed position, a diaphragm, operative connections between said diaphragm and the valve, and a generator connected with the boiler above and below the water level, connections between said generator and the diaphragm whereby, when the water level 110 flows below a predetermined level, the said diaphragm will be caused to operate to unseat the valve, and means independent of said diaphragm for operating the valve and holding the same in any degree of open position. 115

2. The combination with a boiler, a generator, pipes joining said generator with the boiler above and below the water level in the boiler, said pipes being capable of turn- 120 125 130

ing so as to raise or lower the generator, means for feeding water to the boiler, and a regulator under control of said generator for regulating the supply of water to the 5 boiler.

3. The combination with a boiler, of pipes respectively connected with said boiler above and below the water line therein, of a generator connected with said pipes, said pipes 10 being capable of turning on their points of attachment to the boiler so as to raise or lower the generator, means for feeding water to the boiler, and a regulator under control of said generator for regulating the supply 15 of water to the boiler.

4. The combination with a boiler, of a pair of pipes respectively connected with the boiler above and below the water line therein, said pipes being adapted to be turned 20 about their points of connection, of a bent tube connected with the free ends of said pipes, a closed casing surrounding the bent portion of said tube, the said bent portion lying slightly out of a horizontal plane, 25 means for feeding water to the boiler, a regulator for controlling said means, and

connections between said regulator and the said casing, as and for the purpose specified.

5. The combination with a boiler, of a generator connected with said boiler above 30 and below the water level therein, means for feeding water to the boiler, mechanism for controlling said feeding means, said mechanism including a valve casing, a valve in said casing, means for pressing said valve 35 toward its closed position, a threaded valve stem, a diaphragm adapted to act on said stem, connections between said diaphragm and the generator for pressing on the valve stem to open the valve when the water level 40 in the boiler falls, a hand wheel or nut on the valve stem, and stationary means with which said wheel or nut may engage when the wheel or nut is screwed in one direction for depressing the valve stem and holding 45 the valve in open position.

In testimony whereof, I hereunto affix my signature in the presence of two witnesses.

NOIBERTO GUY COPLEY.
